UNITED STATES PATENT OFFICE.

JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

MULTIPLE-COPYING MACHINE.

1,272,787.

Specification of Letters Patent. Patented July 16, 1918.

Application filed January 21, 1916. Serial No. 73,297.

To all whom it may concern:

Be it known that I, JOHN J. FLANIGAN, a citizen of the United States, residing at Chicago, in the county of Cook and State of Illinois, have invented certain new and useful Improvements in Multiple-Copying Machines, of which the following is a specification.

This invention relates to the art of multiple copying machines of the hectograph type, and has reference more particularly to that class of such machines employing a flat printing bed supported on a suitable frame, and a duplicating band or apron stretched thereover between receiving and delivery spools mounted in the frame at opposite ends of the bed respectively.

The primary and general object of the invention is to produce a machine of this type that shall be of simple and durable construction, capable of production at a low cost, easy to operate, and wherein the printing may be effected either by the hand of the operator or by an impression roller or any other impression device. More specific objects are, to provide an improved spool for the copying apron, to provide, in combination with such spool, an improved means for removably mounting and supporting the same in the frame of the machine, to provide an improved gage-bar for positioning and squaring sheets of different widths on the printing bed, and to provide in association with the frame and bed an improved receptacle for containing and housing supplies and accessories of the machine, thus utilizing what would otherwise be waste space in the machine.

Other minor objects and advantages of the invention will be apparent to those familiar with the art from the following description taken in connection with the accompanying drawings forming a part of this specification, in which,—

Figure 1 is a top plan view of the machine;

Fig. 2 is a longitudinal section on the line 2—2 of Fig. 1;

Fig. 3 is a fragmentary side elevation, as viewed from the lower right hand corner of Fig. 1;

Fig. 4 is a view partly in end elevation and partly in vertical section through the frame, the gage-bar, and one of the spools and its mountings;

Fig. 5 is a side elevation of one of the spools; and

Fig. 6 is an end view of the same.

Referring to the drawings and describing first the frame structure and printing bed, 60 10 designates each of a pair of parallel vertical side plates that are rigidly connected and spaced at their lower portions by cross bars 11, the ends of which are turned down to form legs 12 and feet 13, and are secured to the side plates by bolts or rivets 14. 15 designates each of a pair of distance rods that rigidly connect and space the upper portions of the side plates 10 above the cross-bars 11, and form supports for a removable 65 hinged bed plate 16. This latter, as is best shown in Fig. 2, has attached to its opposite sides near its front and rear ends front and rear angle brackets 17 and 18 respectively. The depending portions of the brackets 17 70 are vertically slotted or forked as shown at 19 to straddle and rest upon the forward distance rod 15, and the rear brackets 18 are horizontally slotted or forked as shown at 20 to similarly engage the rear distance 75 rod 15 under a horizontal sliding movement. To remove the bed plate its forward end is raised until the brackets 17 clear the forward distance rod 15, and then by a slight forward movement the rear brackets 18 are 80 drawn clear of the rear distance rod 15. The bed-plate is put in place by the converse of these operations performed in the inverse order in a manner readily understood. The described mounting of the bed-plate also 85 enables it to be tilted up on its rear hinges to afford access to an underlying storage receptacle hereinafter described. The ends of the bed plate 16 are preferably bent 90 downwardly, as shown at 16', in the general direction of the copying apron in passing between the spools or rolls and the ends of the printing bed, to reduce wear on the apron and avoid the necessity of anti-friction rollers at the ends of the bed 95 plate. The bed plate 16 is preferably furnished with a cloth covering 21 stretched thereover and suitably secured thereto. The structural features of the machine as thus far described are, with the exception 100 of the inclined ends of the bed plate, shown, described and claimed in an earlier application filed by me on the 8th day of November 1915 Serial No. 60,251, and no 105 claim thereto is made herein.

Over the bed-plate is stretched the usual gelatin duplicating apron or band 22, the end portions of which are wound on a pair of spools, designated as an entirety by 23, 5 one of which is located at the head end of the machine and constitutes the receiving spool while the other is located at the tail end of the machine and constitutes the delivery spool. When the apron has been exhausted 10 from the delivery spool and wound up on the receiving spool, the two spools are removed and interchanged and the band is then rewound in the same direction, or the spools may be left in place and the band re-wound 15 in the reverse direction. Figs. 4, 5 and 6 illustrate the detail structure of this spool, which comprises a cylindrical body portion 24 preferably of wood or other non-metallic material formed with a longitudinal 20 groove or kerf 25 for the attachment thereto of the end of the duplicating apron. The two ends of the spool body 24 are made polygonal in cross section, as by squaring them, as shown at 26, and these squared ends 25 are provided in their outer faces with outwardly flaring or tapered central recesses or sockets 27 in line with the axis of the spool. Preferably, and as here shown, the squared ends of the spool are also equipped 30 with sheet metal skeins 28 for greater strength and durability, and the outer faces or ends of the skeins are centrally apertured to register with the recesses or sockets 27, and the metal surrounding said apertures is 35 preferably swaged inwardly to form a lining or bushing for the sockets 27, as shown at 29. At the head end of the machine one squared end of one of the spools is engaged with a supporting member 30 that is journaled 40 in one of the side plates of the frame and is provided with a crank arm 31. The inner end of the spool support 30 is formed as a chuck 32 that engages the squared end portion of the spool, and preferably the 45 chuck is further formed with a tapered centering pin 33 lying between the jaws of the chuck that centers the spool in the chuck through engagement with the recess 27. Fast on the chuck is a ratchet disk 34 that 50 is normally engaged by a gravity detent 35 pivoted to the inner face of the side plate of the frame. The last described structure for supporting one end of the spool is duplicated at the tail end of the machine, with 55 the exception that a turning knob 36 (Fig. 1) is substituted for the crank 31.

The other ends of the spool are removably mounted on duplicate supports, each of which, as best shown in Figs. 1, 3 and 4, comprises a supporting member 37 that is rigidly secured at its outer end to, and carried by, a long leaf spring 38, which latter is secured at its intermediate portion as by rivets 39 to the outer side of the opposite side plate 60 of the frame whereby the free end portions of the spring carrying the supporting members 37 can be flexed outwardly from the side plate sufficiently to disengage the spool as hereinafter described. Each supporting member 37 extends through an aperture 40 70 in the side plate of the frame and has formed on its inner face a cone-shaped spindle 41 that normally engages the tapered bearing recess or socket in the proximate end of the spool forming a bearing support 75 on which the latter may freely rotate, and preferably the supporting member 37 is equipped with a stop pin 41' that limits the retracting movement of the supporting member to an extent sufficient to facilitate 80 the application and removal of the spool. Preferably, and as herein shown, each end of the long spring 38 is extended slightly beyond the frame plate, as shown at 38', which facilitates the flexing back of the 85 spring by the thumb of the operator when applied for removing a spool from or positioning it in its bearings. To place the spool in working position either end thereof may be first engaged with its support, and 90 then by flexing the spring end 38' outwardly the other end of the spool may be readily passed into engagement with its support. To remove the spool, the spring is flexed outwardly thus separating the spool supports sufficiently to disengage one end of the spool from its bearing, whereupon the other end may be readily disengaged by a simple longitudinal movement. The described construction of spool mounting has several advantages, among which are the facility with 95 which the spool may be mounted and withdrawn, the accurate centering of the spool, and its security against accidental dislodgment from half bearings or other open-sided 100 bearings.

I have also provided the present machine with an improved gage-bar well adapted for use on machines not employing a platen carriage for rolling out the sheet on the 110 printing bed, and designed to facilitate the accurate and symmetrical positioning of paper sheets of different widths. This gage, in the form herein shown, comprises a gage-bar proper 42 of generally Z form in cross 115 section located directly opposite the head end of the printing bed and having rearwardly extending arms 43 that are pivoted at 44 to the side frame plates of the machine, so that the gage-bar may be tilted back to the dotted line position indicated in Fig. 2 to facilitate the mounting of the copying apron and its rolls or spools. The upper horizontal leaf of the gage-bar 42 is longitudinally slotted as shown at 45, and on the same is mounted an adjustable gage plate or slide 46 having a finger 47 overlying the lower leaf of the gage-bar. The slide 46 is secured at any set position lengthwise of the slot 45 by a thumb screw 48 and nut 49. In copy- 120

125

130

ing a sheet, such as 50, the movable gage plate 46 is adjusted to and fixed in such a position lengthwise of the gage-bar as will determine a symmetrical position of the sheet 50 on the printing bed through engagement of one corner of the sheet with the gage finger 47.

In order to render the machine as compact as possible and utilize what would otherwise be waste space for the storage of accessories and supplies I provide a sheet metal box 51, most clearly shown in Fig. 2, which is disposed between the side frame members and beneath the bed plate. In order to use 15 a receptacle of maximum dimensions, the lower portion of the box 51 is formed with rectangular reentrant ends 51' that, when the box is in position, rest upon and depend from the spacing bars 11 of the frame, the 20 end walls of the box lying just inside the distance rods 15. By either removing or tilting the bed plate upwardly to vertical position, this storage box 51 may be readily applied or removed. The box may be utilized 25 to carry the copying apron and its spools as well as various other accessories of the machine; and since the bed plate in working position forms a cover for the box the latter is well adapted to protect its contents from dust, dirt and injury.

I claim:

1. In a duplicating machine, the combination with a frame structure including parallel side frame members, of a spool for a 35 copying apron having squared ends each provided with a central recess, a supporting member for one end of said spool journaled in one of said side frame members and formed with a chuck adapted to engage one 40 squared end of said spool, and a centering pin adapted to engage the recess in said end, and a supporting member for the other end of said spool mounted in the other side frame member and formed with a non-rotatable 45 spool adapted to engage the recess in the other end of said spool, said spool being yieldable in the direction of the spool axis to permit application and removal of the spool, and said spool being reversible 50 end for end between its supporting members.

2. In a duplicating machine, the combination with a frame structure including parallel side frame members, of a spool for a copying apron having squared ends, each 55 provided with a central recess, a supporting member for one end of said spool journaled in one of said side frame members and formed with a chuck and a centering pin adapted to engage the squared end and recess respectively at one end of said spool, a 60 supporting member for the other end of said spool mounted in the other side frame member and formed with a non-rotatable spool adapted to engage the recess in the other end 65 of said spool, said spool being movable

in the direction of the spool axis, and a spring normally urging said spool into bearing engagement with the end of the spool, said spool being reversible end for end between its supporting members.

70

3. In a duplicating machine, the combination with a frame structure including parallel side frame members, of a reversible spool for a copying apron having squared ends each provided with a central recess, a 75 supporting member for one end of said spool journaled in one of said side frame members and formed with a chuck adapted to engage one squared end of said spool, and a centering pin adapted to engage the recess in said 80 end, a spring secured to the other side frame member, and a supporting member for the other end of the spool directly carried by said spring and formed with a non-rotatable spool adapted to engage the recess in said 85 other end of the spool.

4. In a duplicating machine, the combination with a frame structure including parallel side walls, of a spool for a copying apron having centrally recessed squared 90 ends, a supporting member for one end of said spool journaled in one of said side walls and formed with a chuck adapted to engage one squared end of said spool, a leaf spring secured to the outer side of the other side 95 wall, and a supporting member for the other end of said spool secured to the free end portion of said spring and extending through said side wall, said last named supporting member having its inner end formed as a 100 spindle adapted to engage the recess in said other end of the spool.

5. In a duplicating machine, the combination with a frame structure including parallel side walls, of a pair of spools for a 105 copying apron, each having centrally recessed squared ends, supporting members for corresponding ends of said spools journaled in the opposite ends of one side wall respectively, and each formed with a spool- 110 engaging chuck, a leaf spring secured substantially centrally to the outer side of the other side wall and extending lengthwise of the latter, and a pair of supporting members for the other ends of said spools se- 115 cured to the free end portions of said spring respectively and extending through said other side wall, said last named supporting members having their inner ends formed as spindles adapted to engage the recesses in 120 said other ends of the spools.

6. As a new article of manufacture, a winding spool for a copying apron consisting of a cylindrical body portion and duplicate end portions of polygonal cross-section rigid with said body portion, each of said end portions having formed in its outer face a bearing recess or socket axially coincident with the axis of the spool body.

7. As a new article of manufacture, a 130

winding spool for a copying apron consisting of a cylindrical body portion and duplicate end portions of polygonal cross-section rigid with said body portion, each of said end portions having formed in its outer face an outwardly flaring bearing recess or socket axially coincident with the axis of the spool body.

8. As a new article of manufacture, a winding spool for a copying apron consisting of a cylindrical body portion having a longitudinal kerf and duplicate integral flattened end portions, each of said end portions having formed in its outer face a bearing recess or socket that is axially coincident with the axis of the spool body.

9. As a new article of manufacture, a winding spool for a copying apron, consisting of a non-metallic cylindrical member having squared ends each formed with a central recess or socket in line with the axis of the spool, and metal skeins covering said squared ends and formed with openings in their outer faces registering with said recesses.

10. As a new article of manufacture, a winding spool for a copying apron consisting of a non-metallic cylindrical member having squared ends each formed with a central recess or socket in line with the axis of the spool, and metal skeins covering said squared ends and having on their outer faces inturned portions forming linings for said recesses.

11. As a new article of manufacture, a winding spool for a copying apron consisting of a cylindrical body portion and duplicate end portions of polygonal cross-section, each of said end portions having formed in its outer face an outwardly flaring recess or socket axially coincident with the axis of the spool body, and sheet-metal skeins covering said end portions and formed with openings in their outer faces registering with the outer ends of said recesses.

12. As a new article of manufacture, a winding spool for a copying apron consist-

ing of a cylindrical body portion and duplicate end portions of polygonal cross-section, each of said end portions having formed in its outer face an outwardly flaring recess or socket axially coincident with the axis of the spool body, and sheet-metal skeins covering said end portions and having on their outer faces inwardly swaged portions forming linings for said recesses.

13. In a duplicating machine, the combination with a frame structure including parallel side walls, of a copying-apron spool having squared ends each formed in its outer face with a central outwardly flaring recess, a supporting member for one end of said spool journaled in one of said side walls and formed with a driving chuck and a tapered centering pin for engaging one end of said spool, a leaf spring secured to the outer side of the other side wall, and a supporting member for the other end of said spool secured to said spring and extending through said side wall, said last-named supporting member having its inner end formed as a tapered bearing adapted to engage the recess in said other end of the spool.

14. In a duplicating machine, the combination with a frame structure including parallel side walls, of a copying-apron spool having squared ends each formed in its outer face with a central recess, a supporting member for one end of said spool journaled in one of said side walls and formed with a driving chuck and a centering pin for engaging one end of said spool, a leaf spring secured to the outer side of the other side wall and having its free end projecting beyond the end of the latter to form a finger-hold for flexing the spring outwardly, and a supporting member for the other end of said spool secured to said spring and extending through said side wall, said last-named supporting member at its inner end engaging in the recess in said other end of the spool and serving as a bearing therefor.

JOHN J. FLANIGAN.
